[57] CLAIM

The ornamental design for a pad of paper, as shown and described.

DESCRIPTION

FIG. 1 is a top front perspective view of a pad of paper showing our new design;

FIG. 2 is a front elevational view thereof, it being understood that the undisclosed rear is flat and plain;

FIG. 3 is a right side elevational view thereof, the undisclosed left side being a mirror image; and,

FIG. 4 is a top plan view thereof, the undisclosed bottom being substantially the same.
